UNITED STATES PATENT OFFICE

RUSSEL N. SHEFFLER AND WILLIAM J. SHEFFLER, OF LOS ANGELES, CALIFORNIA

GAME APPARATUS

Application filed December 15, 1931. Serial No. 581,227.

This invention relates to game apparatus, and has particular reference to a mechanical game apparatus simulating the game of basket ball.

5 It is an object of this invention to provide a game board enclosed within a suitable glass-front casing and having "goals" or baskets at the opposite ends of the casing, together with means whereby balls or 10 other projectiles may be propelled from the surface of the game board toward and into the said baskets, suitable means being provided for returning the balls from the baskets onto the game board and into position 15 for further play.

It is an object of this invention to provide a mechanical game apparatus including means whereby a player or players may project the balls or other projectiles into 20 the baskets at opposite ends of the casing, and to provide a trough-like ball accumulating device for receiving the balls from the baskets and retaining them in a position remote from the game board, the passage of 25 balls from the accumulating trough back to the surface of the game board being under the control of the player through the instrumentality of suitable check or coin controlled mechanisms.

30 It is an object of this invention to provide a game apparatus simulating, on a miniature scale, the game of basket ball, and in which the balls pass from the baskets into an accumulating trough, then into a distributing trough and, finally, into a position on the game board surface to be again projected toward and into the baskets at opposite ends of the apparatus, the passage of the balls 35 from the accumulating trough to the distributing trough preferably being under the control of check or coin controlled mechanism, and the passage of the balls from the distributing trough onto the game board being under the control of mechanism whereby 40 the balls are individually and selectively moved from said distributing trough onto the game board where they roll into a position to be engaged by the projecting mechanism.

45 It is a further object of this invention to

provide a game apparatus of the character described in which the game board includes a pair of depressed portions located at each side of the device, each of the depressed portions having a cup-shaped center portion over which the ball will lodge, and to associated with each of the cup-shaped center portions, a manually controlled and operated plunger, by means of which a ball, 55 after coming to rest on the center portion, may be projected toward and/or into the basket at the opposite side of the apparatus, the game board surface being centrally divided and sloping downwardly from said line of division toward the several depressed 60 portions at opposite sides of the game board surface.

It is a still further object of this invention to provide a game apparatus of the character described, in which the game may be 70 played with a predetermined number of balls, say ten, and in which the relative length of the distributing trough with respect to the length of the accumulating trough is so proportioned that regardless of the number of balls retained in the several branches of the accumulating trough, an 75 equal number of balls, say five, will be supplied to the several branches of the distributing trough when the balls are released from 80 their position in the accumulating trough.

It is a still further object of this invention to provide a game apparatus of the character described, which is cheap and easy to manufacture, strong and durable, highly interesting and amusing, and in which the success of the game and the total number of goals or baskets made, is dependent upon the element of chance and upon the skill and dexterity of 85 the competing players.

90 In the accompanying drawings, wherein for the purpose of illustration, we have shown a preferred embodiment of the invention:

95 Figure 1 is a front elevation of a game apparatus made in accordance with our invention,

Fig. 2 is a front elevation of the device, partly in section and illustrating certain features of construction,

100 Fig. 3 is a fragmentary front elevation of

portions of the accumulating and distributing troughs showing the release mechanism for the accumulating trough and the ejecting mechanism for individually and selectively moving the balls from the distributing trough onto the game board surface,

Fig. 4 is a vertical sectional view on the line 4—4 of Fig. 3,

Fig. 5 is a sectional view showing the projecting mechanism, and the ejecting mechanism for individually and selectively moving the balls from the distributing trough onto the game board surface,

Fig. 6 is a perspective view of a portion of the ejecting mechanism, and

Figs. 7 and 8 are perspective views of parts of the mechanism for releasing the balls from the distributing trough.

Referring to the drawings, wherein like reference characters have been employed to illustrate like parts throughout the several views, the numeral 10 designates a box-like casing of wood or other suitable material, having an open front side, a portion of which is preferably covered with glass or other transparent material, below which is a base or panel board 11. The game board 12 is secured within the casing and extends horizontally between the inner side surfaces of the casing 10 in a plane coinciding with the top edge of the base or panel board 11. This game board has its front edge suitably attached to the rear side of the base or panel board 11 and extends rearwardly toward the back of the casing 10, the rear edge of this game board being attached to the front edge of a distributing trough 13, which trough is secured by suitable fastening means (not shown) to the inner surface of the back of the casing 10. Attached to the inner surface of the back of the casing 10 by any suitable fastening means, (not shown) is an accumulating trough 14, the ends of which are shaped to cooperate with the back and side portions of the casing 10 to provide ball-receiving receptacles 15, immediately above which are positioned, in parallel, spaced relation, the semi-annular loops or baskets 16.

The accumulating trough 14 comprises two relatively long branches 17 and 18 which extend downwardly from the receptacles 15 and meet at the center of the back wall of the casing 10. The bottom surface of each of the trough members 17 and 18 is cut out as at 19, so that, under the proper operating conditions, balls rolling down the trough members 17 and 18 may drop through the said openings 19, one at a time, and into the underlying distributing trough 13. The passage of the balls from the accumulation trough 14 is selectively controlled by a V-shaped member 20 which, when in its lowermost position such as shown in full lines in Figs. 2, 3 and 4, constitutes a barrier and prevents the balls from falling through the

openings 19 at the inner ends of the trough members 17 and 18. The V-shaped member 20 is provided with an upstanding lug 21 having a pair of elongated openings 22, adapted to slidably engage the shanks of the attaching screws 23 threaded into the back of the casing 10 to permit limited upward and downward movements of said V-shaped member 20 from the barrier (full-line) position to the non-barrier (dotted line) position shown in the accompanying drawings.

Upward movement of the barrier member 20 may be effected and controlled by any suitable mechanism, coin or check controlled or otherwise, but in the preferred embodiment of this invention, the said member is provided with a depending link 24 having an inturned terminal portion 25, which engages beneath an arm 26 of an L-shaped lever pivotally mounted between spaced lugs carried by the inner surface of the distributing trough 13. The opposite end 27 of the pivoted lever is engaged by the upstanding arm 28 of a reciprocating slide 29 which extends through the front panel 11 of the casing and is provided with a coin or check controlled member 30 of any desired or preferred construction, it being obvious that as the slide 29 is moved toward the back of the casing 10, the upstanding arm 28 will engage the arm 27 of the pivoted lever, this movement causing the arm 26 to lift the link 24 to raise the barrier 20, thus permitting the balls to roll out of the openings 19 and into the distributing trough 13. As soon as all the balls have passed from the accumulating trough 14 into the distributing trough 13, the slide 29 is moved forwardly by the coin or check controlled member 30, whereupon the V-shaped member 20 moves downwardly into its barrier position, which prevents further passage of balls from the accumulating trough 14 until the coin or check controlled mechanism 30 and its associated parts, are again actuated.

The distributing trough 13 comprises two branches 31 and 32 which incline downwardly from a point immediately beneath the center or meeting point of the trough members 17 and 18, the length of the branches 31 and 32 being somewhat less than the length of the overlying trough members 17 and 18 respectively. Or, to state this relationship in another way, the branches 31 and 32 are of such a length or extent that each of them may contain one-half of the total number of balls used in the game, whereas the branches 17 and 18 are of greater length and may each contain more than half of the total number of balls used in the game. The lower end of the front wall of each trough 31 and 32 is cut away as at 33 to form an outlet through which the individual balls may be selectively ejected from the trough members and onto the playing field or game board sur-

face 12. The ejector mechanism for individually moving the balls from the branches 31 and 32 of the distributing trough 13, comprises a plate-like member 34, pivotally mounted between spaced parallel lug members 35 extending beneath the bottom surface of the trough 13, and having an upwardly extending arm 36 which projects through an opening 37 cut through the bottom of each trough member 31 and 32 in back of the outlet opening 33. An operating link 38 is pivotally connected to the plate-like member 34 and extends through the panel board 11 and terminates in a knob 39, it being obvious that as the link 38 is moved outwardly, such movement will rock the plate-like member 34 in a clockwise direction about its pivotal mounting and will cause the arm 36 to move downwardly through the opening 37 and out of the way of the lowermost ball in the trough, which ball will then roll down into the extreme end of the trough and immediately over the hole 37 and the arm 36. Inward movement of the link 38 will cause the member 34 to move in a counterclockwise direction about its pivotal mounting and thus the arm 36 will be moved through the opening 37 and will lift the lowermost ball from the trough and will eject the same through the opening 33 and onto the playing field or game board 12, the presence of the arm 36 now preventing the next ball in the trough from rolling into the extreme end of the trough over the hole 37. In order that the arms 36 will always be in the uppermost position when the barrier member 20 is raised and the balls are rolling into the branches 31 and 32, after the release or upward movement of the barrier 20, a bar member 40 is provided, which is riveted or otherwise attached to the arm 28 and thus moves inwardly as the slide 29 moves inwardly. The ends of this bar 40 engage beneath the bottom edge of the plate 34 and hence the ejector arm 36 is moved to its uppermost position simultaneously with the upward movement of the barrier member 20.

The "playing field" or game board surface of the device comprises a pair of depressed portions 41 and 42 located at each side of the surface, each of the depressed portions having a cup-shaped center portion 43 over which the balls will lodge. That portion of the surface between the pairs of depressed portions 41 and 42 slopes upwardly as at 44 and meets in a centrally-positioned dividing ridge 45.

Each of the cup-shaped depressed portions 43 is provided with a plunger 46 which passes through a suitable opening in the rim portion of the cup-shaped depression and is restricted to limited sliding movements within said opening by means of enlarged head portions on each end of said plunger. The two plungers associated with the depressed portions

41 and 42 at the left side of the device are inclined and directed toward the goal or basket at the right hand side of the device, whereas those plungers associated with the depressed portions 41 and 42 at the right side of the device, are inclined and directed toward the goal or basket at the left hand side of the device, the arrangement being such that if the proper impetus is imparted to the plunger, the ball resting thereabove will be projected toward and into the goal or basket at the opposite end of the game apparatus. Associated with each of the plungers 46 is an actuating lever or "hammer" 47, provided with an enlarged contact portion 48 at its inner end and with a handle portion 49, this lever being pivoted intermediate its ends on the base plate 11. The preponderance of weight of the lever is on that portion which extends into the casing beneath the playing field 12, so that the normal position of the said lever is as shown in full lines in Fig. 5.

Having thus described the construction constituting the preferred embodiment of this invention, we will now describe the operation of the same. Assuming that the game is to be played with a total of ten balls, five of which are to be used by each of the two competing players, a check or coin, say a five cent coin, is inserted in the check or coin controlled device 30 and this device 30 moved inwardly, which moves the slide 29 toward the rear of the cabinet. During this movement of the slide 29, the upstanding arm 28 will engage the arm 27 of the pivoted lever, causing the arm 26 to lift the link 24 to raise the barrier 20, thus permitting the balls to roll out of the openings 19 and into the distributing trough 13. Simultaneously with the rearward movement of the slide 29 and the arm 28, the bar 40 carried by the arm 28 moves rearwardly, the end portions of this bar contacting with the lower edge of the member 34 and, hence, the ejector arm 36 is moved to its uppermost position simultaneously with the upward movement of the barrier member 20. Regardless of the number of balls contained in each of the branches 17 and 18 of the accumulating trough, said balls will roll down the said branches and through the openings 19 and will be distributed in equal numbers in the branches 31 and 32 of the distributing trough 13, it being noted that the said branches 31 and 32 are of a length sufficient to accommodate therein a predetermined number of balls, say one-half of the total number of balls with which the game is being played.

Let it be assumed, for the purpose of illustration, that the branch 17 contains seven balls and that the branch 18 contains three balls, the said balls, upon the upward movement of the barrier 20, will roll from the branches 17 and 18 and into the branches 31 and 32, respectively, of the underlying distributing trough 13. The

balls from the branch 17 will fill up the branch 31 with five of the seven balls and the three balls from branch 18 will partially fill the branch 32, the sixth and seventh balls falling from the branch 17 contacting with the fifth ball in the branch 31 and rolling into the branch 32, thus assuring a proper and equal distribution of balls to the branches 31 and 32 of the distributing trough, it being noted that during this distribution, the ejector head 36 is in its uppermost position which prevents the balls from rolling out of the discharge end of the branches 31 and 32.

As soon as the balls are properly distributed as above described, one of the players pulls outwardly on the knob 39, which moves the rod 38 outwardly, thus moving the member 34 in a clockwise direction about its pivotal mounting to move the arm 36 into the opening 37 to a position shown in full lines in Fig. 5, thus permitting the lowermost ball to roll downwardly and to occupy a position at the extreme lower end of the branch and directly over the opening 37. Inward movement of the rod 38 reverses the direction of movement of the member 34 and causes the arm to move to the position shown in dotted lines in Fig. 5, thus pushing the overlying ball through the opening 33 onto the playing field or game board surface. The said ball will roll over one of the adjacent cup-shaped depressions 43 in position to be projected toward the baskets or loops 16 at the opposite side of the game apparatus. The player then pushes downwardly upon the handle portion 49 which moves the lever 47 upwardly to cause the hammer portion 48 to deliver a sharp, quick blow to the lower end of the plunger 46. Assuming that the proper impetus has been imparted to the plunger, the ball will be projected into one of the loops or baskets 16 and into the underlying receptacle 15, from which it will roll into the associated branch of the accumulation trough and against the barrier 20 which has previously moved to its lowermost position. If, on the other hand, the necessary and proper impetus has not been imparted to the plunger, the ball will either strike the edge of one of the members 16 or will fall short of the baskets and will rebound to the game board surface and onto one of the cup-shaped depressions 43 on either side of the dividing ridge 45. If the rebound is such that the ball rolls over one of the cup-shaped depressions 43 on that side of the apparatus from which it was previously projected, then the player has another chance to try for a goal with the same ball, but if it rolls over one of the cup-shaped depressions 43 on the opposite side of the apparatus, then the competing player secures the advantage of an additional ball.

If the first player makes a goal or basket then the competing player actuates the ejector

mechanism to move a ball from his side of the distributing trough onto the adjacent portion of the playing field or game board, from which it is projected toward the opposite side of the game apparatus in the manner above described. The game is terminated when all ten balls have been played from the field into the baskets and have descended into the receptacle 15 and into the inclined troughs for redistribution to the lower distributing trough, the passage of the balls from the accumulation trough to the distributing trough being under the control of the check or coin device and its associated mechanism. If desired, the casing 10 may be provided with a plurality of balls or buttons strung on a rod or wire to assist in keeping a score of the goals, baskets or plays made by the individual players.

It is to be understood that the form of our invention herein shown and described is to be taken as a preferred embodiment of the same and that various changes may be made in the shape, size and arrangement of parts without departing from the spirit of the invention or the scope of the subjoined claims.

Having thus described our invention, we claim:

1. A game apparatus comprising a horizontally disposed game board, goals disposed above the board at opposite sides thereof, means for projecting balls from the game board into the goals, downwardly-inclined accumulating troughs extending from each of the goals and meeting at a point above the center of said game board for receiving balls from the goals, a discharge opening for the balls being provided at the meeting portion of said troughs, a barrier for the said discharge opening which when in one position prevents the passage of balls through the opening and when in another position permits the balls to pass through the opening and from the accumulating troughs, and means to actuate the said movable barrier to permit the passage of balls from the accumulating troughs onto the game board for further play.

2. A game apparatus comprising a horizontally disposed game board, goals disposed above the board at opposite sides thereof, means for projecting balls from the game board into the goals, downwardly-inclined accumulating troughs extending from each goal and meeting at a point above the center of said game board for receiving balls from the goals, a discharge opening for the balls being provided in the bottom of each trough at the meeting portions of said troughs, a vertically movable barrier for the bottom discharge opening which when in its lowermost position prevents the passage of balls through the opening and when in its uppermost position permits the balls to pass through the opening and from the accumulating trough, and means for moving the barrier to its up-

permost position to permit the passage of balls from the accumulating troughs onto the game board for further play.

3. A game apparatus comprising a horizontally disposed game board, goals disposed above the board at opposite sides thereof means for projecting balls from the game board into the goals, a receptacle below each of said goals into which the balls pass, a downwardly inclined accumulating trough extending from each of said receptacles, and meeting at a point above the center of said game board, a discharge opening for the balls being provided at the meeting portions of said troughs, a barrier for said discharge opening for retaining said balls in said troughs, and means to move the barrier to permit the passage of balls through the discharge opening from the accumulating trough onto the game board for further play.

4. A game apparatus comprising a horizontally disposed game board, goals disposed above the board at opposite sides thereof, means for projecting balls from the game board into the goals, downwardly inclined accumulating troughs extending from each of said goals and meeting at a point above the center of said game board for receiving the balls from the goals, a discharge opening for the balls being provided through the bottom of each trough at the meeting portions of said troughs, a vertically-movable barrier disposed within the opening discharge which barrier when in its lowermost position prevents the passage of balls through the opening and when in its uppermost position permits the balls to pass through the opening from the accumulating troughs, an operating rod for the barrier, and a connection between the operating rod and said barrier whereby movement of the operating rod elevates the barrier to permit the balls to pass through the opening from the accumulating troughs onto the game board for further play.

5. A game apparatus comprising a horizontally disposed game board, goals disposed above the board at opposite sides thereof, means for projecting balls from the game board into the goals, downwardly-inclined accumulating troughs extending from each of said goals and meeting at a point above the center of said game board for receiving balls from the goals, a discharge opening for the balls being provided through the bottom of each trough at the meeting portions of said troughs, a vertically movable barrier disposed within the opening which barrier when in its lowermost position prevents the passage of balls through the opening from the trough and when in its uppermost position permits the balls to pass through the opening from the accumulating troughs, a vertically-disposed link attached to said barrier, a hori-

zontally-extending operating rod terminating adjacent the lower end of said link, and a pivoted lever located between the lower end of said link and the adjacent end of said operating rod whereby movement of said rod will elevate said link to lift the barrier to permit the balls to pass through the opening from the accumulating troughs onto the game board surface for further play.

6. A game apparatus comprising a game board, goals disposed above the board, means for projecting balls from the game board into the goals, an accumulating trough for receiving the balls from the goals, a distributing trough below said accumulating trough, means for controlling the passage of balls from said accumulating trough into said distributing trough, and means associated with said distributing trough for individually and selectively moving the balls from said distributing trough onto the game board surface for further play.

7. A game apparatus comprising a game board, goals disposed above the board, means for projecting balls from the game board into the goals, an accumulating trough for receiving the balls from the goals, a distributing trough below said accumulating trough, a barrier at the discharge end of the accumulating trough, a barrier at the discharge end of the distributing trough, and means for moving the accumulating trough barrier to permit the passage of balls into the distributing trough and simultaneously moving the distributing trough barrier to prevent the passage of balls from the distributing trough onto the game board.

8. A game apparatus comprising a game board, goals disposed above the board, means for projecting balls from the game board into the goals, an accumulating trough for receiving the balls from the goals, a distributing trough below said accumulating trough, a barrier at the discharge end of the accumulating trough, a barrier at the discharge end of the distributing trough, means for moving the accumulating trough barrier to permit the passage of balls into the distributing trough and simultaneously moving the distributing trough barrier to prevent the passage of balls from the distributing trough, and means for moving the distributing trough barrier to permit the passage of balls from said trough onto the game board for further play.

9. A game apparatus comprising a game board, goals disposed above the board, means for projecting balls from the game board into the goals, an accumulating trough for receiving balls from the goals, a distributing trough below said accumulating trough, a barrier at the discharge end of the accumulating trough which when in one position permits the passage of the balls from the accumulating trough to the distributing trough and

- when in another position prevents such passage, a combined barrier and ejector at the discharge end of the distributing trough which when in one position prevents the passage of balls from said trough and when in another position permits the balls to roll into a position to be ejected from the discharge end of the said distributing trough, and means for actuating the said barriers.
10. A game apparatus comprising a game board, goals disposed above the board, means for projecting balls from the game board into the goals, a distributing trough for receiving balls from the goals, said trough having a discharge opening adjacent the game board surface, a pivoted member having a portion adapted to extend through the bottom of the discharge trough near the discharge opening therein, and means for moving said member about its pivotal mounting to move a ball through the discharge opening and onto the game board for further play.
11. A game apparatus comprising a casing, a game board located at the bottom of the casing, goals disposed above the board on opposite sides of said casing, means for projecting balls from the game board into the goals, an accumulating trough comprising downwardly inclined branches leading from a position beneath the goals and meeting near the center of the casing, said branches each being of sufficient length to accommodate more than half of the total number of balls used in the game, a distributing trough below said accumulating trough comprising downwardly inclined branches each being of a length to accommodate only one-half of the total number of balls used in the game, means for controlling the passage of said balls from said accumulating trough into said distributing trough, and means associated with each of the distributing troughs for individually and selectively moving the balls from each branch onto the game board surface for further play.
12. A game apparatus comprising a casing; a game board located at the bottom of the casing; goals disposed above the board on opposite sides of said casing; receptacles below said goals into which the balls may pass; an accumulating trough comprising downwardly inclined trough members leading from said receptacles and meeting near the center portion of said casing, said troughs being of a sufficient length to accommodate more than half of the total number of balls used in the game; a distributing trough below said accumulating trough comprising branches inclining downwardly from beneath the meeting point of the trough members of the accumulating trough, each of said branches being of a length to accommodate only one-half of the total number of balls used in the game; a barrier for controlling the passage of balls from said accumulating trough into said distributing trough; a combined barrier and ball ejector at the discharge end of each branch of the distributing trough; means to actuate the barrier of the accumulating trough and the combined barrier and ejector of the distributing trough to simultaneously move the barrier of the accumulating trough to permit the passage of balls therefrom and to prevent the passage of balls from the discharge end of the distributing trough; and means to move the combined barrier and ball ejector independently of the movement of the accumulating trough barriers.
13. A game apparatus comprising a horizontally disposed game board, goals disposed above the game board at opposite sides thereof, means at opposite ends of the game board for projecting balls from the game board into the goals, accumulating troughs for receiving the balls from the goals and discharging them at a point above the center of said game board, and means extending from below the discharge point of the accumulating troughs for conveying the balls to the projecting means at opposite ends of the game board.
14. A game apparatus comprising a horizontally disposed game board, goals disposed above the game board at opposite sides thereof, means at opposite ends of the game board for projecting balls from the game board into the goals, downwardly inclined accumulating troughs extending from each of said goals for receiving the balls from the goals and discharging them at a point above the center of said game board, and distributing troughs extending from below the discharge point of the accumulating troughs for conveying the balls to the projecting means at opposite ends of the game board.
- In testimony whereof we hereunto affix our signatures.
